UNITED STATES PATENT OFFICE.

CHARLES S. CASE, OF BINGHAMTON, NEW YORK.

TOE AND INSTEP STRETCHER FOR BOOTS OR SHOES.

SPECIFICATION forming part of Letters Patent No. 310,380, dated January 6, 1885.

Application filed October 14, 1882. (No model.)

To all whom it may concern:

Be it known that I, CHARLES S. CASE, a citizen of the United States, residing at Binghamton, in the county of Broome and State of New York, have invented certain new and useful Improvements in Toe and Instep Stretchers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Similar letters refer to similar parts throughout the several views.

The object of my invention is to furnish a means by which boots and shoes may be stretched in a particular place, more especially at the toe and instep, without injury to the fit of the other parts; and I accomplish this by means of the last or tree shown in the drawings.

Figure 1 is an outline view of the last, and Fig. 2 is a view of a longitudinal section of it when it is divided vertically.

It may be constructed as follows: Take an ordinary last, cut off the heel, then saw the last lengthwise horizontally into the three parts C, D, and E, and hinge them together by means of the hinge-joints A and B, as shown in the drawings. The rod F is of iron, made long enough to admit of use in a boot, with a T-handle at the top by which to turn it, and the sleeve G is of gas-pipe or other suitable material, just large enough to turn or slide on the rod F without injuring the screw-thread cut on the lower part of it, made somewhat shorter than the rod F, and with a T-handle at the upper end, and screw-threads are cut on the lower part of both rod and sleeve, as shown.

In the bottom of the section E, near the heel, is a plate, J, fastened to the bottom of the last, with a hole through it and through the last for the rod F. The rod is shouldered down near the end, and the small part, without screw, is riveted loosely in the plate J, and turns in the plate, and the shoulder of the rod bears on the top of the plate. The plate is thickened where the rod passes through it and countersunk on the outer or lower side

for the head formed by riveting the rod; or it may be made by letting in an uncut nut in which to rivet the rod, and fastening a thin plate on the bottom of the last to cover it.

In the section D, near the heel and over the bearing-nut J, a hole is made to allow the passage of the rod F, which has a screw-thread from the shoulder at J upward, and this hole must be slightly elongated, so as not to cramp on the rod as the section works up and down on the rod. In the upper part of the section D at this hole the threaded nut I is let in, through which the rod F works. To keep the nut in place, it must be covered by a plate screwed or otherwise fastened to the wood. The nut must be left with a little play to work back and forth as the section D, in which it is confined, is raised or lowered by turning the rod F, and will work easier if the top of the nut is slightly oval. It will be readily seen that by turning the rod and forcing down the heel part of D any required amount of pressure upward at the toe may be produced. If it is desired to stretch some particular place, the well-known "bunion" now in common use may be placed on the last at that point; but care must be taken or a hole will be torn in the shoe, as the pressure is very great.

In the section C, over the holes in the other sections, is a slot made large enough to allow the sleeve G to pass through it. On the under side of the section C is a threaded nut, H, to work on the thread on the lower end of the sleeve G, and this nut may be set in and confined in the same way as above described for the nut I. The end of the sleeve G bears on the plate which covers the nut I, and it will be seen that turning this sleeve will force up the section C as far as may be desired to stretch the instep of a boot.

I am aware that a boot-tree is in use having an instep-stretcher similar to the one here shown, and I do not claim this as my invention, except as used in combination with the other parts of the device.

The hinge A may be made with a tongue on each of its flat surfaces, and a groove made in each of the sections D and E for it to slide in, if desired, and when so made may be adjusted according to the use required; but I do not consider this desirable or necessary.

The heel L and wedge K are the same as in

common use, and the point of greatest pressure at the toe may be varied by making the wedge K thick or thin, as occasion demands, and the whole last may be made of iron, if 5 greater strength and durability are required. The sleeve G may also be made with a nut in the lower end working on the thread on the rod F and a flange on the sleeve to raise the section C.

10 Having thus described my invention and the method of its construction, what I claim as new, and desire to secure by Letters Patent, is—

The toe and instep stretcher composed of the sections D and E, hinge A, rod F, nut I, 15 and plate J, combined with the section C, hinge B, sleeve G, and nut H, and constructed and operating substantially as shown and described.

In testimony whereof I affix my signature in 2c presence of two witnesses.

CHARLES S. CASE.
